UNITED STATES PATENT OFFICE.

ROYER S. BUCH, OF YORK, PENNSYLVANIA.

MOLDER'S FLASK.

1,385,818.

Specification of Letters Patent.

Patented Apr. 6, 1920.

Application filed April 8, 1919. Serial No. 288,617.

To all whom it may concern:

Be it known that I, ROYER S. BUCH, a citizen of the United States, residing at York, in the county of York and State of Pennsylvania, have invented certain new and useful Improvements in Molders' Flasks, of which the following is a specification.

One object of my invention is to provide a molder's flask which will have corrugated 10 side and end sections, preferably of sheet metal, so as to give firmness and strength to the flask and at the same time make it of light weight.

Another object is to so construct my improved flask that the sand will freely flow 15 into engagement with the sides and ends during the jolting or ramming of the sand within the flask.

A still further object is to prevent the 20 sand from shifting within the flask, which prior to my invention often occurred and caused injury to the mold and loss to the operator.

Another object is to so construct my improved flask that it will hold the sand in its 25 proper position regardless of what action takes place in the "rolling-over" or ramming and for this reason alone my improved flask is a practical improvement in 30 the art.

A still further object is to connect the corrugated side and end sections with malleable or steel corners which are corrugated to register with the corrugated side and end 35 sections so as to make a positively rigid structure which will not spring or change its position at the corners while being handled during the molding process.

A still further object is to so construct my 40 improved flask that the corners can be easily and quickly removed and replaced.

Another object is to provide the cope and drag parts with pin connections, certain of the pins being adjustable so as to permit 45 contraction and expansion without bending or jamming any of the elements comprising the flask and at the same time to so arrange the pins that they will serve as centering members for keeping the parts in proper 50 registration with each other.

These objects, and other advantageous ends which will be described hereinafter, I attain in the following manner, reference being had to the accompanying drawings in 55 which

Figure 1 is a top plan view of my improved flask.

Fig. 2 is a side elevation of the flask shown in Fig. 1.

Fig. 3 is an outside elevation of the left 60 hand end of my improved flask, as shown in Fig. 1.

Fig. 4 is an outside elevation of the right 65 hand end of my improved flask, as shown in Fig. 1.

Fig. 5 is a sectional end elevation taken on the line 5—5 of Fig. 2.

Fig. 6 is a longitudinal sectional elevation taken on the line 6—6 of Fig. 1, the same being drawn on an enlarged scale with a portion of its length broken away at its center, 70

Fig. 7 is a fragmentary section through one of the corners and taken on the line 7—7 of Fig. 1.

Fig. 8 is a fragmentary sectional plan view 75 taken on the line 8—8 of Fig. 4, said section being taken through the adjustable pin connection,

Fig. 9 is a fragmentary sectional plan view taken on the line 9—9 of Fig. 4 through 80 one of the hollow reinforcing ribs of the corners,

Fig. 10 is a fragmentary section taken on the line 10—10 of Fig. 2 through a coupling plate which connects the side sections of the 85 cope and drag,

Fig. 11 is an edge elevation of an end or side section having a greater number of corrugations than the end and side sections shown in the foregoing figures and can be 90 made of a greater height than said sections,

Fig. 12 is a side elevation of Fig. 11 showing a portion of the length thereof,

Fig. 13 is an edge elevation of an end or side section having a greater number of corrugations than the end and side sections shown in the above mentioned figures and can be made of a greater height than said sections, and 95

Fig. 14 is an elevation of Fig. 13 showing 100 a portion of the length thereof.

Referring to Figs. 1 to 10 inclusive of the drawings, 20 represents my improved flask having a cope 21 and a drag 22. The cope 21 and drag 22 are each made in the form 105 of a frame which is open at its top and bottom and each frame includes two oppositely disposed side sections 23 and 24 and two oppositely disposed end sections 25 and 26. These end and side sections, as illustrated, 110

are made of corrugated sheet metal, the corrugations 27 thereof running in the direction of the length of said end and side sections. Thus the inner surfaces of each of the 5 end and side sections include inwardly projecting ribs 28 and grooves 29. The ribs 28 and grooves 29 smoothly blend with each other and are curved in cross section so as to produce a series of compound or ogee 10 curves. The top and bottom edge portions of each of the side and end sections, both in the cope and drag, are preferably bent at an angle inwardly to produce flanges 30 which extend entirely around the sides and ends 15 of the cope and drag. By pressing or rolling the corrugations 27 into the respective sections, the outer surface of all of said sections will likewise be formed with a series of outwardly projecting ribs 31 and grooves 20 32. The end and side sections, both in the cope and drag, are respectively secured together by corner sections 33. These corner sections have their inner surfaces corrugated so as to provide inwardly projecting ribs 34 25 and grooves 35 which respectively fit the grooves 32 and ribs 31 in the outer surface of the end and side sections above described. In other words, the corrugations of the corner sections 33 intermesh with the corruga- 30 tions of the end and side sections.

In order to provide additional reinforcement for the corners of the flask, I provide angular plates 36 which are corrugated so as to intermesh with the grooves 29 and rib 35 28 of the corrugations 27. The end and side sections adjacent the corners are clamped between the corner sections 33 and the plates 36, as clearly shown in Fig. 8, by bolts 40 and in order to make a strong and neat 40 connection and abutment for the end edges of the end sections and side sections, I preferably make the corner sections of such thickness, as shown at 37, as to extend in contact with the plates 36 at their points of 45 bend. This construction also provides shoulders 38 against which the end and side sections abut. The corner sections 33 include hollow outwardly projecting ribs 39 which are clearly shown in cross section in Fig. 7.

50 As shown in Figs. 1, 5 and 10, the cope 21 has sand supporting bars 41 extending transversely thereof, said sand supporting bars having their opposite end portions 42 and 43 shaped to intermesh with the ribs 28 55 and grooves 29 of the side sections 23 and 24, as shown in Figs. 5 and 10. Thus the ribs 28 and grooves 29 form slideways for the sand supporting bars 41 so that the sand supporting bars can be easily slid into various positions within the length of the flask 60 and at the same time are prevented from falling out of the flask.

The curvature of the ribs 28 and grooves 29 of the corrugations 27 is such as to permit the sand to freely flow and engage all

70 portions of the inner surfaces of the end sections and side sections, both in the cope and drag so that when ramming or jolting, the sand will engage the inner surfaces with substantially the same pressure at all points. 75 This prevents the sand from sagging, shifting or moving away from the side surfaces and at the same time provides a secure holding means for the body of sand within the flask.

75 The drag 22 at opposite ends has brackets 44 secured thereto by bolts 45. The brackets 44 have pins 46 and 47 which are threaded at their lower ends and secured by nuts 48. The pins 46 and 47 extend upwardly beyond 80 the parting between the drag and the cope as clearly shown in Figs. 2, 3, 4 and 6. The pin 46 extends through a hole 49 in a bracket 50, said bracket being secured to the end section 25 of the cope 21. The pin 46 and 85 bracket 50 form centering means to hold the cope and drag in register. The pin 47, as illustrated, is preferably made square in cross section and slidably fits within a channel 51. The channel 51 has a head 52 which 90 is secured to a bracket 53 by bolts 54. The bracket 53 is secured to the end section 26 by bolts 55. The channel 51, as clearly shown in Figs. 1, 2, 6 and 8 depends within a sleeve 56 formed in said bracket 53. The 95 head 52 rests upon the top of the bracket 53 and is held thereto, as previously stated by the bolts 54. By this construction, the pin 47 is permitted to move within the channel 51 in the direction of the length of the flask 100 so as to permit expansion and contraction or any slight variation or difference in the length of the cope and drag. At the same time the cope can be freely lifted from the drag or replaced thereon.

105 I preferably provide corrugated coupling plates 57 so as to bridge the parting 58 between the cope and the drag; the corrugations of said coupling plates 57 intermeshing with the ribs 31 and grooves 32 on the side 110 sections 23 and 24 of the flask. The side sections 23 and 24 have holes 59 (see Fig. 10) through which tongues 60 project, said tongues having flared heads 61 for engagement with the inner surfaces of said side 115 sections. The tongues 60 project through holes 62 in the coupling plates 57 and are slotted at 63 to permit split wedge pins 64 to be passed therethrough, so as to bind the coupling plates 57 to the respective side sections of the cope and drag. Thus the coupling plates 57 act to clamp the side sections of the cope and drag together but can be easily removed, when it is desired to separate the cope from the drag, by knocking 120 the split wedge pins 64 out of the slots 63.

125 By using the construction above described it is an easy matter to vary the depth of the flask by using side and end sections of various heights, such for example as shown in 130

Figs. 11 to 14 inclusive, said figures being drawn on the scale, for example as shown in Figs. 1, 2, 3, 4, 5, 7, 8, 9 and 10 and are therefore of greater heights than the end and side sections of said latter mentioned figures; the increase in the height being produced by including more corrugations therein. For example considering that the end and side sections, as shown in Figs. 1, 2, 3, 4, 5, 7, 8, 9 and 10 are three inches in height and that the height of the sections shown in Figs. 11 and 13, respectively, are four and five inches in height. It is possible to quickly build up flasks of various depths by using end and side sections of various heights. This is an advantageous feature in the construction of flasks, since it is possible to quickly make up flasks of various depths in which the cope and drag can be made of the same or different heights; it merely being necessary for the foundryman to keep in stock corrugated sections of various heights.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

- 35 1. A flask having corrugated sides; and sand supporting members having ends fitting said corrugations, whereby said members are slidably supported on said sides; substantially as described.
- 40 2. A flask having corrugated end and side sections; and detachable corners for securing said sections together, said corners having portions extending between the ends of the sections and forming shoulders for abutment with the ends of said sections; substantially as described.
- 45 3. A flask having corrugated end and side

sections; and detachable corners for securing said sections together, said corners having corrugations intermeshing with the corrugations of said sections and providing shoulders for abutment with the ends of said sections, whereby the portions of said corners between the shoulders form a continuation of the inner surfaces of said side and end sections; substantially as described.

4. A flask including two parts one above the other; a pin secured to one of said parts for forming a coupling with the other of said parts and having a connection with said latter part slidable in the direction of the length of the flask to permit variation or difference in the length of said two parts due to natural causes; substantially as described.

5. A flask including two parts; a pin secured to one of said parts; and a bracket secured to the other of said parts and having a channel therein into which said pin projects, whereby said channel and pin can move relatively to each other in the direction of the length of said flask; substantially as described.

6. A flask including two parts; a pin secured to one of said parts; and a bracket secured to the other of said parts and having a channel therein into which said pin projects, whereby said channel and pin can move relatively to each other in the direction of the length of said flask, said channel being detachably connected to said bracket; substantially as described.

7. A flask made in two parts and having a coupling plate extending across the parting between said parts; and means for detachably connecting said coupling plate to both of said parts; substantially as described.

In testimony whereof I have signed my name to this specification in the presence of two subscribing witnesses.

ROYER S. BUCH.
